UNITED STATES PATENT OFFICE.

GEORGE P. STANLEY, OF DIXFIELD, MAINE, ASSIGNOR TO BEERST-FORSTER-DIXFIELD COMPANY, OF DIXFIELD, MAINE, A CORPORATION OF MAINE.

MACHINE FOR MAKING TOOTHPICKS AND THE LIKE.

Application filed February 20, 1926. Serial No. 89,569.

This invention relates to machines for making round toothpicks, skewers and similar articles; having especial reference to that type of machine whereby splints are supplied singly to a peripherally grooved or pocketed carrier which advances them in rapid succession to the path of an element operative to effect the rotation of the splints about their own axes and in contact with an abrading wheel which is located exteriorly of and adjacent to the splint carrier and is adapted to reduce the splints to the desired form; such, for example, as illustrated in Letters Patent of the United States No. 661,642, dated November 13, 1900.

My invention, generally stated, comprises improvements in the construction and mounting of the splint carrier, and in a novel arrangement and mounting of the splint-rotating element in such cooperative relation to the said carrier and the abrading wheel that the entire surface of each splint is effectually subjected to the action of the abrading wheel, together with various features of construction and combinations of parts, all of which will be hereinafter described and claimed.

In the drawings—

Figure 1 is a side elevation of a toothpick machine embodying my invention.

Fig. 2 is an end elevation of the machine.

Fig. 3 is a plan of the same.

Fig. 4 is a sectional detail of the adjacent peripheral portions of the splint carrier and the abrading wheel.

Fig. 5 is a transverse vertical section through the splint carrier and associated parts, as on the line 5—5 of Fig. 1.

Fig. 6 is a longitudinal vertical section, as on the line 6—6 of Fig. 5.

Referring to the drawings, 10 designates a supporting frame including a bed 11; and 12 designates the main drive shaft journaled in suitably located bearings below the bed.

A peripherally-grooved splint carrier comprising two counterpart spaced-apart annular members 13 are mounted for concurrent rotation through an opening in the bed, which members are provided throughout their circumference with transverse grooves 14 arranged in spaced parallel relation. The grooves of the two members are in longitudinal alignment with each other, each pair of aligning grooves being formed

to receive and support the respective ends 55 of a splint which bridges the space between the two members. Each annular member is laterally recessed adjacent its periphery, as at 15, and is rotatably seated on a fixed circular head 16. In the present instance 60 the head is formed with an outwardly projecting supporting member 17 which rests upon and is bolted to the bed 11. Secured by screws 17, or other means, to the outer edge of each annulus are spaced-apart clips 65 or lugs 18 which flank the adjacent face of the fixed bearing head 16 and maintain the annular member to its seat; and similarly secured to such edge is an external annular gear 19 which meshes with a pinion 70 20 on a transverse shaft 21 journaled in boxes 22 on the bed, whereby when the shaft 21 is actuated the motion is transmitted therefrom to the annular members 13, thus rotating them as a unit. As a means to 75 rotate the shaft 21 it is provided at one end with a sheave 23 which is connected with and driven from a sheave 24 on a shaft 25 at the rear of the bed 11 by a belt 26, which latter sheave is equipped with a face gear 27 80 in mesh with a pinion 28 on a stud-shaft 29 projecting from the bed. This stud-shaft is provided with a sheave 30 which, in turn, is connected to the main shaft 12 by a crossed belt 31.

Splints are supplied in any suitable manner to the upper peripheral portion of the rotating annular members 13 so as to be severally seated in and carried by the successive grooves. The means illustrated for this purpose comprises an elongated splint-feeding trough 32 which is supported by a pair of side brackets 33 extending from a block 34 bolted to a bifurcated standard 35 rising from the front end of the bed 11. 85 This standard straddles the splint carrier in the vicinity of the abrading wheel. The delivery end of the trough overhangs the annular members and is provided with a transverse splint separating and positioning 90 roll 36 which is arranged in close relation to the grooved peripheries of the said members and is rotatable in an opposite direction thereto so as to permit the passage of the descending splints from the hopper singly 95 to the successively advancing grooves. The shaft 37 of this roll has its bearings in the sides of the trough and also in a bracket

38 extending from the standard 35, and is driven by suitable gearing hereinafter described.

5 Mounted in front of the annular splint carrier is an abrading wheel 39 having a slightly concaved periphery which rotates in proximity to the grooved periphery of the splint carrier, the peripheries of the respective members of the latter being shaped 10 to accord with the curvature of the wheel, as shown most clearly in Fig. 4. The concave periphery of the abrading wheel presents an uninterrupted abrading surface which spans the space between the respective 15 members of the carrier and affords a splint bearing portion directly opposite to the pressure roll. This abrading wheel is fast on a shaft 40 which has its bearings in spaced-apart boxes 41 on the bed 11, and is provided 20 at one end with a pulley 42 that is connected by means of a belt 43 with a pulley 44 on the main shaft. In this way the abrading wheel is rotated reversely of the splint carrier. The boxes 41 are preferably slidably 25 mounted on the bed and are connected to suitable adjusting screws *a* mounted in bearing blocks *b* on the bed, so that by manipulation of the screws the boxes, together with the abrading wheel, can be nicely adjusted 30 toward or from the splint carrier, as desired. Bolts *c*, entering the bed through elongated holes in the bases of the boxes, serve to maintain the boxes in their positions of adjustment.

35 In the space between the annular members of the splint carrier is mounted a roll 45, of rubber or other yielding substance, the periphery of which roll rotates through an arc at or adjacent the periphery of the splint carrier, and thence the splints seated in the 40 grooves of and borne by the carrier come successively in contact with the periphery of the roll as they approach the abrading wheel. This roll 45 is driven at high speed and in 45 the same direction as the abrading wheel, and hence when the succeeding splints come in contact with the roll they are yieldingly pressed thereby against and throughout the width of the uninterrupted peripheral surface of the abrading wheel and are thus independently rotated on their own axes within 50 the grooves of the carrier. Consequently the entire surface of each splint is brought in rolling contact with the concave periphery of the abrading wheel, and the splint is 55 perfectly reduced to circular form in cross-section, tapering at each end to a point.

60 The shaft 46 of the roll extends through an elongated opening 47 in one of the fixed circular heads 16 and has its bearings in a bracket 48 mounted on the adjacent supporting member 17. This bracket is preferably secured to the member 17 by bolts 49 passing through elongated slots in the bracket, 65 so that the bracket, together with the shaft

and the roll, can be adjusted longitudinally of the bed in order to set the periphery of the roll in accurate operative relation to the grooves of the splint carrier. Fixed on the shaft 46 is a sheave 50 which is connected 70 with and driven from the pulley 42 on the shaft 40 by means of a belt 51.

Motion is transmitted from the shaft 46 to the shaft 37 of the splint separating and positioning roll 36 hereinbefore mentioned 75 through a train of reducing gears, comprising gears 52, 53 fast on the respective shafts 46, 37, and intermeshing idlers 54, which idlers are mounted on studs 55 projecting from a bracket 56 on the bifurcated standard 35 which is bolted to the bed. It is to be noted that motion is transmitted from the abrading wheel shaft 40 to the respective rolls 45 and 36, thus availing of the momentum of the heavy abrading wheel to facilitate 80 the rotation of the two rolls.

The standard 35 supports a pair of strips 57 having depending segmental fingers 58 which overlie the grooved peripheries of the annular members 13 of the splint carrier, 90 thus preventing the displacement of the splints as they progress to the bite of the roll 45 and the abrading wheel 39.

From the foregoing it will be seen that all the moving elements, including the internal pressure roll, of a machine embodying my invention, are positively and continuously rotatable on their own axes, thus ensuring a balanced and rapid operation of the machine, and further that by the novel mounting of the said pressure roll within the annular splint carrier and in co-operative relation to the abrading wheel the splints borne by the carrier are individually subjected in rapid succession throughout their entire surfaces to the efficient rounding and polishing action of the wheel, thus producing smooth uniform toothpicks or similar articles.

It is to be understood that my invention 110 is not limited to the details of construction herein disclosed, as the mechanism may be modified within the principle of the invention and the scope of the appended claims.

I claim—

1. The combination of a splint carrier comprising spaced-apart members mounted for unitary rotation and having corresponding peripheral splint-holding grooves, a yielding pressure roll arranged interiorly of the said carrier and having its periphery rotatable in proximity to the grooved periphery of the carrier, an abrading wheel mounted exteriorly of and adjacent the grooved periphery of the carrier, said wheel having its periphery slightly concaved from side to side thereof and presenting an uninterrupted abrading surface which spans the space between the said carrier members and affords a splint bearing portion directly 130

opposite to the pressure roll, and mechanism for rotating the splint carrier in one direction and for rotating the pressure roll and abrading wheel in a direction reversely of that of the carrier, whereby splints borne by the carrier are individually advanced between the opposing peripheries of the pressure roll and abrading wheel and are independently rotated on their own axes by the direct counteracting rotative forces of said roll and wheel so as to present the entire surface of each splint to the action of the abrading wheel.

2. The combination of a splint carrier comprising spaced-apart annular members provided with corresponding peripheral splint-holding grooves, stationary bearing heads on which the respective members are mounted for unitary rotation, a yielding pressure roll arranged interiorly of the carrier and having its periphery rotatable in proximity to the grooved periphery of the carrier, an abrading wheel mounted exteriorly of and adjacent the grooved periphery of the carrier, and mechanism for rotating the splint carrier in one direction and for rotating the pressure roll and abrading wheel in a direction reversely of that of the carrier, whereby the splints borne by the carrier are individually advanced between the opposing peripheries of the pressure roll and abrading wheel and are thereby independently rotated to present the entire surface of each splint to the action of the abrading wheel.

3. The combination with a splint carrier comprising spaced-apart annular members provided with corresponding peripheral splint-holding grooves, stationary bearing heads on which the respective members are mounted for unitary rotation, annular gears on said members, pinions in mesh with said gears, and means for supporting and rotating said pinions, of a yielding pressure roll arranged interiorly of the carrier and having its periphery rotatable in proximity to the grooved periphery of the carrier, a shaft for said roll extending laterally of the carrier, an abrading wheel mounted exteriorly of and adjacent the grooved periphery of the carrier, and means for rotating said abrading wheel and roll in a direction reversely of that of the carrier.

4. The combination of a splint carrier comprising spaced-apart annular members provided with corresponding peripheral splint-holding grooves, stationary bearing heads on which the respective members are mounted for unitary rotation, means for continuously rotating said members, means comprising a feed trough and a separating and positioning roll for supplying splints to the grooves of said carrier, a yielding pressure roll arranged interiorly of the carrier and having its periphery rotatable in

proximity to the grooved periphery of the carrier, a shaft for said roll extending laterally of the carrier, an abrading wheel mounted exteriorly of and adjacent the grooved periphery of the carrier, means for 70 rotating said abrading wheel, operative connection between the said wheel and the shaft of the pressure roll, and operative connection between the said shaft and the separating and positioning roll.

5. The combination of a splint carrier comprising spaced-apart members mounted for unitary rotation and having corresponding peripheral splint-holding grooves, a yielding pressure roll arranged interiorly 80 of the said carrier and having its periphery rotatable in close relation to the grooved periphery of said carrier, means for adjusting said roll toward and from the periphery of the splint carrier, an abrading wheel 85 mounted exteriorly of and adjacent the grooved periphery of the carrier, said wheel having its periphery slightly concaved from side to side thereof and presenting an uninterrupted abrading surface which spans the 90 space between the said carrier members and affords a splint bearing portion directly opposite to the pressure roll, and mechanism for rotating the pressure roll and the abrading wheel in a direction reversely of that of 95 the carrier, whereby splints borne by the carrier are individually advanced between the opposing peripheries of the pressure roll and abrading wheel and are independently rotated on their own axes by the 100 counter-acting rotative forces of said roll and wheel so as to present the entire surface of each splint to the action of the abrading wheel.

6. The combination of a splint carrier comprising spaced-apart annular members provided with corresponding peripheral splint holding grooves, stationary bearing heads on which the respective members are mounted for unitary rotation, means for continuously rotating said members, a yielding pressure roll arranged interiorly of the carrier and having its periphery rotatable in proximity to the grooved periphery of the carrier, a shaft for said roll extending laterally of the carrier, a bearing member for 110 said shaft mounted for adjustment toward and from the periphery of the carrier, means for securing said bearing member in its positions of adjustment, an abrading wheel 115 mounted exteriorly of and adjacent the grooved periphery of the carrier, and mechanism for rotating the pressure roll and the abrading wheel in a direction reversely of that of the carrier.

7. The combination of a splint carrier comprising spaced-apart members mounted for unitary rotation and having corresponding peripheral splint-holding grooves, a yielding pressure roll arranged interiorly 120 of

the said carrier and having its periphery rotatable in close relation to the grooved periphery of said carrier, an abrading wheel mounted exteriorly of and adjacent the grooved periphery of the carrier, said wheel having its periphery slightly concaved from side to side thereof and presenting an uninterrupted abrading surface which spans the space between the said carrier members and affords a splint bearing portion directly opposite to the pressure roll, means for adjusting said wheel toward and from the periphery of the carrier, and mechanism for rotating the pressure roll and the abrading

wheel in a direction reversely of that of the carrier, whereby splints borne by the carrier are individually advanced between the opposing peripheries of the pressure roll and abrading wheel and are independently rotated on their own axes by the counter-acting rotative forces of said roll and wheel so as to present the entire surface of each splint to the action of the abrading wheel. 15 20

Signed at Dixfield in the county of Oxford and State of Maine this 11th day of Feb. 25 A. D., 1926.

GEORGE P. STANLEY.
